Primary Examiner — Jennifer Rivard(74) *Attorney, Agent, or Firm* — Wolf, Greenfield & Sacks, P.C.(57) **CLAIM**

The ornamental design for a hand held dermaplaning device, as shown and described.

DESCRIPTION

FIG. 1 is a top, front, right side perspective view of a hand held dermaplaning device according to my new design; FIG. 2 is a top, rear, left side perspective view of FIG. 1; FIG. 3 is a front elevation view of FIG. 1; FIG. 4 is a rear elevation view of FIG. 1; FIG. 5 is a left side elevation view of FIG. 1; FIG. 6 is a right side elevation view of FIG. 1; FIG. 7 is a top plan view of FIG. 1; FIG. 8 is a bottom plan view of FIG. 1; and, FIG. 9 is a bottom perspective view of FIG. 1. The dash-dash broken lines show portions of the hand held dermaplaning device that form no part of the claimed design.

1 Claim, 5 Drawing Sheets(56)
